(57) **CLAIM**

The ornamental design for a sensor housing, as shown and described.

DESCRIPTION

FIG. 1 is a front view of a sensor housing design; FIG. 2 is a lower perspective view of the sensor housing design of FIG. 1; FIG. 3 is an upper perspective view of the sensor housing design of FIG. 1; FIG. 4 is a rear view of the sensor housing design of FIG. 1; FIG. 5 is a left side view of the sensor housing design of FIG. 1; FIG. 6 is a right side view of the sensor housing design of FIG. 1; FIG. 7 is a top view of the sensor housing design of FIG. 1; and, FIG. 8 is a bottom view of the sensor housing design of FIG. 1.

The broken lines shown in the drawings are included for the purpose of illustrating the unclaimed portions of the sensor housing. The broken lines form no part of the claimed design.

1 Claim, 8 Drawing Sheets
